UNITED STATES PATENT OFFICE.

JAMES H. RAND, OF NORTH TONAWANDA, NEW YORK, ASSIGNOR, BY MESNE ASSIGNMENTS, TO RAND KARDEX BUREAU, INC., OF TONAWANDA, NEW YORK, A CORPORATION OF DELAWARE.

INDEX TAB.

Application filed March 2, 1923. Serial No. 622,411.

This invention relates to index devices and pertains more particularly to the construction of tabs of the kind commonly employed in connection with index guide cards, folders, etc., for holding index slips, label and the like. In the accompanying drawings a preferred embodiment of the invention is illustrated by way of example and in such drawings;

10 Figure 1 is a fragmentary perspective view of the upper portion of a guide card or folder having a tab of the improved construction secured thereto;

Figure 2 is a vertical cross-section on the 15 line 2—2 of Fig. 1;

Figure 3 is a similar vertical cross-section but illustrating a modification; and

Figure 4 is also a vertical cross-section illustrating a further modification.

20 One form of tab which is common and in extensive use consists of a strip of thin transparent sheet celluloid bent to form an open-ended label-holding pocket of substantially triangular cross section and an attaching element whereby the tab may be secured to a guide card, folder, or other support.

That portion of the tab which projects beyond the edge of the card and which forms the label receiving pocket usually has 30 one of its side walls inclined to the plane of the card. The label or index slip is placed within the pocket behind the inclined side of the tab through which it is visible and by which it is protected from dirt and injury. If the label or index slip be of relatively stiff material and of proper width, it remains indefinitely in the desired position immediately behind the inclined wall of the pocket, as the convergence of the opposite sides of the pocket prevents it from slipping out of place. If, however, the index slip be soft and without substantial inherent stiffness or if it be substantially narrower than the width of the inclined wall of the 40 pocket, it tends to drop away from the latter so as to be visible with difficulty if at all. In accordance with the present invention the tab is provided with a retaining element or detent so disposed as to prevent slipping or displacement of the label, even though the latter be soft and flimsy or of less than normal width.

In the following description the term "card" is employed as a convenient generic

term to designate any of the usual forms of support such as separator cards, folders, etc., to which index tabs are commonly applied. In Figs. 1 and 2 the numeral 1 indicates a card, to which the tab 2 forming the subject-matter of the present invention is secured. 55 This tab is preferably made from a strip of transparent sheet celluloid bent at the points 3, 4 and 5 to form an open ended pocket of substantially triangular cross section for the reception of the removable index slip or label 14. This pocket 6 is defined by the side walls 7, 9, and 10 respectively, the side 60 7 being extended as indicated at 8 to form an attaching member by which the tab is secured to the card 1. The side 10 of the 65 pocket is preferably inclined at an angle to the plane of the attaching member 8 and the label 14 is positioned immediately beneath this inclined side wall, the inclination of 70 which is such as to facilitate reading of the inscription upon the label when the tab is mounted upon the guide card. One end portion of the strip of celluloid is bent to provide the member 11 which extends substantially parallel to the member 7, but spaced 75 slightly therefrom to admit the upper portion of the card between them. As the material of the tab is somewhat resilient the pinching of the upper edge of the card between the members 7 and 11 may be sufficient 80 to retain the tab in operative position, although it is preferred to employ some adhesive material for permanently securing the part 8 to the face of the card. The end portion of the strip is bent at the point 12 85 to provide the resilient detent 13 which lies substantially parallel to the side wall 10 of the pocket, being spaced slightly from the latter to admit the index slip 14 between them. As the detent engages the slip intermediate its longitudinal margins, the slip 90 is held closely in engagement with the wall 10 and is prevented from dropping away from the latter even though it be of relatively thin and flimsy material or substantially narrower than the width of the wall 10. If desired the space between the members 10 and 13 may normally be substantially 95 less than the thickness of the index slip to be employed, and in inserting the latter the member 13 would first be sprung away from the wall 10 and after the slip had been positioned, the return of the member 13 to nor-

mal position would serve to hold the slip firmly in position.

In the modification shown in Fig. 3 the card or support is indicated at 1^a. The tab 5 is shown as comprising a strip bent at the points 3^a, 4^a and 5^a to form an open ended pocket of substantially triangular cross-section having the side walls 7^a 9^a and 10^a, the latter being that through which the index 10 slip is visible. The wall 7^a is continued to provide the attaching element 8^a which is cemented to the card or otherwise secured thereto. The end portion of the strip is continued beyond the bend 5^a to form the detent 15 element 11^a whose extremity is spaced slightly from the central portion of the wall 10^a so as to hold the index slip 14^a firmly against the inner surface of such wall.

In the arrangement shown in Fig. 4 the 20 card is indicated at 1^b and the tab is shown as comprising a strip of material bent at the points 3^b, 4^b, 15 and 17 to provide an open ended pocket of substantially triangular form having the side walls 7^b, 10^b and 16. 25 The side wall 7^b is extended to provide the attaching element 8^b while the opposite end portion of the strip is continued beyond the bend 17 to form the additional attaching element 18, the upper portion of the card 1^b 30 being received between the members 8^b and 18. The resiliency of these members may be depended upon for holding the index tab in position although it is preferred to employ cement or other adhesive as additional securing means. In this form of the device the bending of the material at the points 4^b and 15 provides the short wall element 9^b which lies substantially parallel to the wall 11^b of the pocket and provides a recess within 35 which the lower edge of the index slip 14^b is received. This recess serves to retain the slip in proper position against the inner surface of the wall 10^b.

While transparent celluloid is desirable as 40 material for forming the tab in accordance with the present invention, it is contemplated that other sheet material, preferably resilient and preferably transparent may be employed for the purpose, although if the material is not transparent it may be furnished with an aperture or window in that side of the pocket through which the label is to be viewed and such aperture may, if desired, be provided with a separate protective sheet of celluloid, glass or the like for preventing defacement of the label which is 45 50 55

held in proper operative position by the retaining elements or their equivalents, here described.

I claim:

1. An index tab formed from a strip of transparent sheet material bent to provide side walls extending at an angle to each other forming a pocket, an element integral with one of said walls and movable relatively thereto for engaging the rear side of an index slip intermediate its longitudinal margins to hold it in substantial contact with an inner surface of an imperforate side wall of the pocket. 60 65 70

2. An index tab made of transparent sheet material bent to form an open ended pocket having an inclined integral front wall constructed and arranged to exhibit an index slip positioned within the pocket, and comprising a resilient detent integral with the material of the pocket for holding the index slip in contact with the inner surface of said inclined front wall. 75 70

3. An index tab comprising a strip of transparent sheet material bent to form a pocket for the reception of an index slip, one extremity of said strip being disposed within the pocket and constituting a retaining element for holding the index slip in contact with an inner wall of the pocket. 80 85

4. An index tab comprising a strip of transparent celluloid bent to provide a pocket for the reception of an index slip, one end portion of said strip being disposed within the pocket and in a plane substantially parallel to one side wall of the pocket to permit the introduction of an index slip between them. 90 95

5. An index tab made of a strip of transparent celluloid bent to provide an attaching member and an open ended pocket of substantially triangular cross section having one wall thereof inclined to the plane of the attaching member, one end portion of the strip being bent to lie in a plane substantially parallel to the attaching portion, providing a space therebetween for the reception of a supporting card, and being further bent to form a member extending substantially parallel to the inclined wall of the pocket for resiliently pressing an index slip against the latter. 100 105

Signed by me at Boston, Mass., this 23rd day of February 1923.

JAMES H. RAND.
